NOSE CAP

Ernst Zeidler, Frankfort-on-the-Main, Germany,
assignor to Vereinigte Deutsche Metallwerke
Aktiengesellschaft, Frankfort - on - the - Main,
Germany, a corporation of Germany

Original application November 9, 1935, Serial No.
49,010. Divided and this application August
10, 1937, Serial No. 158,306. In Germany
November 13, 1934

5 Claims. (Cl. 170—177)

This invention relates to means for detachably connecting a one-piece nose cap, protecting the hubs of airscrews, to the hub at several points simultaneously.

5 The attachment and also the dismounting of airscrew nose caps on and from the hub has hitherto usually been a matter taking up a good deal of time, since most of such nose caps consisted of a plurality of parts which had to be attached to the hub individually, by means of screws, bolts and the like. It has therefore been proposed to make the caps in one piece and arrange for the attachment to be as simple as possible. A conventional method of mounting, which was also 10 the simplest, was by means of a clamping band or cord. This method had the great disadvantage that, in the event of the band being damaged only in one place, the band or cord dropped off and the cap was flung off the hub by the action of centrifugal force.

It is an object of the present invention to eliminate the disadvantages of conventional nose caps and to provide a one-piece nose cap capable of being detachably connected or locked to the hub at any convenient number of points, by a 15 turn of the hand.

To this end, according to the invention, a rotatable or expandable locking means is provided which carries all the fixing members jointly, and 20 which is indirectly or directly connected to the hub.

In the case of conventional nose caps having a plurality of parts, it is known to connect such parts together, at several points simultaneously, 25 by locking devices. However, these conventional devices did not solve the problem contemplated by the present invention, to wit: the provision of an easily operated method of connection and release between a one-piece nose cap and the air-screw, or its hub.

The design of the detachable connection of the present invention may vary in point of detail provided that the foregoing condition is fulfilled. For example, it may be established by means of a 30 rotatable ring, engaging by means of slots, with corresponding pins on the cap, or conversely, by means of pins engaging in slots in the cap and thus enabling the locking to be effected at any 35 number of points simultaneously. These pins which lock the cap may also be designed as rotatable or sliding bolts, controlled by the rotatable ring. It is also possible to interconnect articulated lever-like bolts adapted to be actuated 40 jointly and controlled by a push bar in such a manner that said bolts can be brought into en-

gagement with corresponding slots in the one-piece cap.

A special advantage is obtained by combining with the locking arrangement, safety devices for securing same and coming into operation at the same time as the former.

In order more clearly to understand the invention, reference is made to the accompanying drawing which illustrates diagrammatically and by way of example, several embodiments thereof. 10

In said drawing:—

Fig. 1 illustrates a side elevational view, somewhat fragmentary and having parts cut away, of an exemplary embodiment of the invention in which a nose cap is provided with a plurality of 15 pins engaging slots in a rotatable ring;

Fig. 2 depicts a vertical sectional view, also fragmentary, taken on line 2—2 of Fig. 1;

Fig. 3 shows a longitudinal and fragmentary sectional view of a modified embodiment of the 20 invention in which a plurality of slots is provided in the nose cap, and a rotatable ring carrying a pin for each of said slots cooperates with said nose cap;

Fig. 4 is a fragmentary plan view of the embodiment illustrated in Fig. 3;

Fig. 5 illustrates a front elevational view, somewhat fragmentary and having parts in section, of another embodiment of the invention including a pivoted bolt lever engaging through corresponding openings in the nose cap and controlled by a rotatable ring;

Fig. 6 depicts a vertical sectional view taken on line 6—6 of Fig. 5;

Fig. 7 shows a front elevational view somewhat fragmentary and having parts in section, of a further embodiment of the invention embodying radially displaceable bolt levers;

Fig. 8 is a vertical sectional view taken on line 8—8 of Fig. 7; and

Fig. 9 shows another arrangement embodying the principles of the invention in which pivoted expandible bolt levers are provided capable of being brought into and out of engagement with slots in the nose cap.

In the embodiment according to Figs. 1 and 2, a plate 1, the rim of which is bent round at an angle at 1', in the direction of the engine is secured to the body of the hub 3 of the airscrew, for example by means of screws 2. Below the annular flange 1' of the plate 1, and bearing against the latter, is a flat ring 4 provided with holes 9 which merge, on the one side, into slots 10. The plate 1 is also provided with holes corresponding to the holes 9 in the ring 4.

The one-piece nose cap 5, which is suitably cut away for the passage of the airscrew blades, bears, by means of its inwardly turned rim 6, on the plate 1, secured to the hub 3 on the side remote from the ring 4. The nose cap 5 is centered by means of a ring 7, surrounding (for example, riveted on) the annular flange 1', and the cap is supported by means of a plate 5' mounted on the inside of the cap 5 and adapted to slip over the outer end of the hub 3. The rim 6 of the nose cap carries pins 8 which are provided with annular grooves and coact with the holes 9 in the ring 4 and plate 1. A lug 11, on the ring, and serving as a handle for rotatively displacing the ring 4, protrudes through corresponding slots in the annular flange 1' and ring 7.

In assembling the cap 5, the pins 8 attached thereto penetrate through the holes 9 in the plate 1 and ring 4, said holes being at first in alignment. 20 Rotatively displacing the ring 4 by means of the lug 11 is all that is now needed to bring the lateral slots 10 into engagement with the grooves in the pins 8, and thus lock the cap 5 at any convenient number of points, in accordance with 25 the number of pins 8 and openings 9, 10 provided. To release the nose cap 5, the ring 4 is turned in the opposite direction until the pins 8 come out of the slots 10, and the holes 9 in the ring 4 are again in alignment with the corresponding 30 holes in the plate 1, whereupon the nose cap can be dismounted without any further manipulation.

In the modified embodiment illustrated in Figs. 3 and 4, the outer ring 12 which centers the nose cap 16 on the annular flange of the plate 13 attached to the hub, is adapted to be rotatively displaced by means of the handle 12', and is provided with the locking pins 14 which are passed inwards through longitudinal holes 15 in the annular flange of the plate 13. The length of 40 the holes 15 determines the extent to which the ring 12 can be rotated. The cap 16 is provided with bayonet-catch slots 17 on the rim adapted to be inserted between 12 and 1. In addition, the annular flange of the plate 13 carries a pin 45 13' on which fits the slots 16' in the nose cap. As is evident from Fig. 4, from which the outer ring 12 is omitted, all that is necessary, after the cap 16 has been slipped into place, is to turn the ring 12 so that its pin 14 enters the bayonet-catch 50 slot 17, and thereby lock the nose cap at any convenient number of points.

Figs. 3 and 4 also show a safety catch which comes into operation at the same time as the locking device. Secured (for example, riveted) 55 on the annular flange of the plate 13, at 19, is a flat spring 18 carrying a stud 20. Directly the ring 12 has arrived in the locking position, said stud 20 springs through the annular flange of the plate 13 into a hole in the ring 12 and thus prevents the latter from accidental reversion. In order to release the cap 16, the catch stud 20 must first be pushed inwards, before the ring 12 can be turned back.

According to Figs. 5 and 6, the plate 21, which is attached to the hub and over the marginal flange of which the cap 27 is slipped, is provided with rotatably mounted or pivoted levers or bolts 22, the one arm of which is engaged by pins 23, seated on the ring 24, which is adapted to be rotated by means of the handle 24', said pins enabling the other arm to enter at 25 corresponding slots 26 in the cap 27, directly the ring 24 is rotatably displaced in the one direction by means 70 of the handle 24'. The broken lines in Fig. 6

represent the pivoted lever or bolt 22 in the released position.

In the example shown in Figs. 7 and 8, the locking of the cap 34 with the plate 28 attached to the hub is effected by means of radially displaceable bolts or push bars 29 which engage, by means of pins 30, in oblique slots 31 in the ring 32 rotatively displaceable by the handle 32', and are guided by fillets 28' attached to the plate 28. When the ring 32 is suitably rotated, the ends 33 of the bars 29 enter openings in the cap 34 and lock the latter as shown in Figs. 7 and 8. For the release, the ring 32 is turned the other way, the bars 29 being so controlled by the oblique slots 31 that their ends 33 release the cap 34. 15

In the example according to Fig. 9, lever mechanism is provided for locking the cap 48. This mechanism comprises the levers 35 which, at the ends provided with the locking noses 36—for example, on the plate (not shown) attached to the hub of the airscrew—are rotatably mounted, the other end being provided with slots 37. Levers 35 are pivoted in pins 41. Slots 37 are engaged by pins 38 seated on the bar 39 which is adapted to be moved in the longitudinal direction by hand. On said bar being moved in the direction of the arrow, the levers 35 are turned through the agency of the pin-and-slot guides 37, 38, so as to bring their locking noses out of engagement with the nose cap 48. 20

The present application is a division of my co-pending application, Serial No. 49,010, filed on November 9th, 1935, now Patent No. 2,092,901, granted on September 14, 1937, and entitled "Nose cap". 35

I claim:—

1. In an aircraft propeller, the combination comprising an airscrew, a hub associated with said airscrew, a one-piece nose cap covering said hub, a supporting member rigidly connected to said hub having a supporting surface conforming to the terminal surface of said nose cap, a plurality of slots in said terminal surface, fixing means including displaceable bolts associated with said supporting member adapted to selectively engage said slots in the nose cap, and manually operable elements adapted to simultaneously displace said bolts from an inoperative position into an operative position. 40

2. In an aircraft propeller, the combination comprising an airscrew, a hub associated with said airscrew, a one-piece nose cap covering said hub, a supporting member rigidly connected to said hub having a supporting surface conforming to the terminal surface of said nose cap, a plurality of slots in said terminal surface, fixing means including displaceable bolts associated with said supporting member adapted to selectively engage said slots in the nose cap, and means including a manually operable ring-like locking member adapted to simultaneously displace said bolts from an inoperative into an operative position. 50

3. In an aircraft propeller, the combination comprising an airscrew, a hub associated with said airscrew, a one-piece nose cap covering said hub, a supporting member rigidly fastened to said hub having a supporting surface conforming to the terminal surface of said nose cap, a plurality of radially displaceable bolts associated with said supporting surface, a slot in said nose cap for each of said bolts, and a rotatable ring-like member adapted to collectively displace said bolts from an inoperative into an operative position to engage said slots and to hold said nose cap. 60

4. In an aircraft propeller, the combination comprising an airscrew, a hub associated with said airscrew, a one-piece nose cap covering said hub, a supporting member rigidly fastened to said hub and having a supporting surface conforming to the terminal surface of said nose cap, a plurality of pivoted bolts associated with said supporting surface, a slot in the terminal portion of said nose cap for each of said bolts, and a manually operative ring-like member co-operating with said bolts and capable of simultaneously turning said bolts around said pivots to engage said slots and to hold said nose cap.
5. In an aircraft propeller, the combination

comprising an airscrew, a hub associated with said airscrew, a one-piece nose cap covering said hub, a supporting member rigidly fastened to said hub and having a supporting surface conforming to the terminal portion of said nose cap, a plurality of slots in the terminal portion of said nose cap, a pivoted lever bolt for each of said slots mounted on said supporting member one end of said lever bolts being adapted to engage said slots, and a push bar engaging the other end of said lever bolts and adapted to move same from an inoperative into an operative position to engage said slots and to retain said nose cap.
